UNITED STATES PATENT OFFICE

LAWRENCE A. HYLAND, OF WASHINGTON, DISTRICT OF COLUMBIA, ASSIGNOR TO WIRED RADIO, INC., OF NEW YORK, N. Y., A CORPORATION OF DELAWARE

HIGH FREQUENCY STABILIZER

Application filed May 6, 1929. Serial No. 360,906.

My invention relates broadly to the frequency control of high frequency systems from a remote source.

One of the objects of my invention is to provide a remote control system for stabilizing the frequency of a radio transmitter.

Another object of my invention is to provide a remote control system wherein the frequency characteristics of a remotely located circuit are maintained substantially constant.

Still another object of my invention is to provide a frequency control system wherein the frequency of the energy emanated from a transmitting station is automatically controlled in accordance with the frequency from a remotely located constant frequency station.

Other and further objects of my invention reside in certain circuit arrangements for obtaining the desired operating characteristics, a better understanding of which can be had from the specification following and the accompanying drawings, wherein:

Figure 1 is a schematic circuit diagram showing the remote standard frequency control station and Fig. 2 is a schematic circuit diagram showing a high frequency transmitter the frequency characteristics of which are controlled in accordance with my invention.

My system for the remote control of high frequency circuits employs a synchroscope adjusting arrangement somewhat similar to that shown and described in my copending application Serial No. 350,053, filed March 26, 1929, entitled "High frequency stabilizers" now Patent No. 1,822,812, issued September 8, 1931, and my copending application Serial No. 359,381, filed April 30, 1929.

A suitable mechanically vibratile element serves as a standard of frequency. Fig. 1 of the accompanying drawings shows element 7 as a piezo electric crystal, however any suitable means may be employed as an initial frequency standard. Element 7 is connected with the input circuit of thermionic tube oscillator 6. The output circuit of thermionic tube 6 is connected with the input circuit of thermionic tube rectifier 8. The out-

put circuit of thermionic tube rectifier 8 is connected with a multi-vibrator or subharmonic circuit comprising thermionic tubes 9 and 10. This circuit is adapted to produce subharmonics of the frequency of the exciting source as described by Messrs. Lewis M. Hull and James K. Clapp, in "Proceedings of the Institute of Radio Engineers", volume 17—pages 252-271, February, 1929, in an article entitled "A convenient method for referring secondary frequency standards to a standard time interval".

Any suitable arrangement may be employed to produce the subharmonic frequencies other than the arrangement illustrated. In the arrangement shown it is possible to produce a subharmonic of a value one-fiftieth of the frequency value of the exciting source.

The arrangement shown depends for its operation upon a number of factors, primarily the asymmetry of thermionic tubes 9 and 10, or, the equivalent, the asymmetry of their circuits. Thermionic tubes having unlike characteristics may be employed or the effective characteristics of like tubes caused to vary by means of resistors 30, 31 connected with their respective anodes. These resistors may be of values having ratios substantially 50 to 1 or other ratio as determined from experiment. Condensers 32, 33 contribute to the operating characteristics and assist in establishing the desired condition for producing submultiples of the exciting energy.

By exciting energy is meant the energy from the output circuit of thermionic tube rectifier 8. Thermionic tube 8 may be of any suitable type other than that shown such as, for instance, of the shield anode type or shield control electrode type. This may be desirable to prevent interaction from the "multivibrator" as pointed out in the article by Hull and Clapp referred to above.

Again, I desire it to be known that it is not essential to my invention that the "multivibrator" illustrated in the accompanying drawings be employed. Any suitable system for producing submultiple frequencies may be employed.

The transmitter proper comprises thermionic tube oscillator 26 having input and output circuits for producing oscillations of high

frequency energy. The output of thermionic tube 26 is delivered to the input circuit of thermionic tube amplifier 27. The output of thermionic tube 27 is delivered to space 5 radio radiating system 29 as shown, or may be delivered to any desired load circuit such as a wired radio system. Thermionic tube 13 is fundamentally a rectifier having a divided input circuit comprising coils 11 and 12. Coil 12 is in inductive relation to the output circuit of thermionic tube 27 or in other manner related with the energy in this circuit. Coil 11 is similarly associated with constant frequency oscillator standard 6. 10 Energy from the output of amplifier 27 and energy from oscillator 6 is coupled into the input circuit of thermionic tube rectifier 13. The output circuit of rectifier 13 comprises coils 14 and 15 wherein is present the beat 15 frequency of the difference of the frequencies of oscillator 6 and the output of amplifier 27. The output energy of subharmonic producer 9-10 is connected with winding 20 of transformer 21. Winding 22 of transformer 21 20 is connected with thermionic tube 23. The output circuit of thermionic tube 23 comprises coils 16 and 17 and phase-splitting circuit 18, 19. Coils 16 and 17 are positioned substantially at right angles to each other and 25 suitably supported on a pivot which allows free movement of the coils.

Coils 14 and 15 are positioned substantially as schematically illustrated, in inductive relation to coils 16-17. Coils 16-17 30 cooperatively actuate condenser 25 by means of mechanical connection 24 or in any suitable manner. My copending application, Serial No. 850,053, now Patent No. 1,822,812, issued September 8, 1931, describes the adjustable 35 frequency control in more detail.

The operation may be summed up as follows: Suppose, for example, it is desired to generate and transmit energy from oscillator 26 having a frequency of 510 kilocycles. The 40 power rating of thermionic tube 26 may be of the order of 10 kilowatts. Mechanically vibratile element 7 may be chosen to have a fundamental frequency of 500 kilocycles. The energy from oscillator 6 transferred to 45 the input circuit of thermionic tube 13 would have a frequency of 500 kilocycles. The frequency of the energy from oscillator 26 transferred to the input circuit of thermionic tube 13 would have a frequency of 510 kilocycles.

In the output circuit of thermionic tube 50 55 13 comprising coils 14 and 15, a beat frequency of 10 kilocycles is present. The frequency of the energy transferred from oscillator 6 to thermionic tube 8 will be 500 kilocycles. Selecting the 50th submultiple 60 frequency of this value means that the input circuit of thermionic tube 23 will have a current having a frequency of 10 kilocycles. The current of 10 kilocycle frequency from 65 thermionic tube 23 energizes movable coils

16-17 at this frequency. Since the excitation of coils 14-15 is by current of like frequency value, no torque is exerted upon coils 16-17.

If, however, the frequency of the energy 70 from oscillator 26 should reduce to 509.5 kilocycles instead of the desired value of 510 kilocycles, the energization of coils 14-15 would be at 9.5 kilocycles instead of 10 kilocycles. This difference would be sufficient 75 to produce a torque which would act upon coils 16-17 moving the same from their normal position. This motion is in turn transmitted by suitable means, represented at 24, to any suitable frequency controlling device 80 herein represented as condenser 25. The motion transmitted to condenser 25 may be sufficient to correct the adjustment of frequency, as in the example above, and to increase the frequency characteristics of the oscillatory 85 circuit to the amount of 500 cycles or .5 kilocycle to reestablish the generation of the 510 kilocycle energy. In like manner, should the frequency from oscillator 26 increase to 510.5 kilocycles instead of remaining at 510 90 kilocycles, the beat frequency would be .5 kilocycle. Since the difference between the 9.5 kilocycle beat frequency in coils 14-15 and the 10 kilocycle frequency in coils 16-17 is 500 cycles, a torque would be exerted upon 95 movable coils 16-17 causing a displacement of the movable coils. From first consideration it would seem that the 500 cycle increase of frequency or the 500 cycle decrease of frequency would effect a similar displacement 100 of the movable coil and that no stability results. It must be remembered that the beat frequency in coils 14-15 in the first instance was 9.5 kilocycles, but in the latter instance is 10.5 kilocycles. 105

The frequency of the energy in coils 16-17 remains constant at 10 kilocycles. Between the frequency of energy in coils 16-17 and the frequency of the energy in coils 14-15, in the first instance, the difference was .5 110 kilocycle. The solution rests on the fact that in the former instance the frequency of the energy in coils 14-15 was 9.5 kilocycles while in the latter instance the frequency is 10.5 kilocycles. It is obvious that an equal 115 torque will be produced in either instance. It is also obvious that the displacement of the movable coils will be of a like amount. It will be observed, however, that the displacement in the first instance will be in the opposite direction to the displacement in the latter instance. Movable coils 16-17 are not set at zero beat but are moved an appreciable displacement from such position. This allows the movement in either direction. When 120 the frequency of the energy in coils 14-15 increases, coils 16-17 will be moved in a given direction. When the frequency decreases, coils 16-17 will be moved in the 125 opposite direction. 120

The foregoing description largely applies to the station located at a distant point, the frequency of which is controlled by the constant frequency transmitter shown in Fig. 1. 5 Fig. 2 shows such a station located at a remote point, the frequency of which is controlled from such a constant frequency transmitter as is represented in Fig. 1.

In general the reference characters in Fig. 10 2 are those employed in Fig. 1 with the difference that in Fig. 2 each character has the suffix "a". The receiving system proper comprises any suitable energy collecting system, herein represented as directional coil antenna 15 7a, which is connected with a suitable high frequency amplifier circuit herein represented by thermionic tube 6a. Coil antenna 7a serves to collect the high frequency energy of constant frequency from the transmitter illustrated in Fig. 1. High frequency amplifier 20 6a amplifies the incoming signaling energy which, in the example chosen, is of the order of 510 kilocycles. This energy of 510 kilocycle frequency is delivered to the input circuit of thermionic tube rectifier 8a. The output of rectifier 8a is associated with a sub-harmonic producer 9a-10a. Resistors 30a, 31a and condensers 32a, 33a serve to produce the necessary asymmetry of thermionic tubes 25 9a, 10a. The output is connected with winding 20a of transformer 21a. The 51st sub-harmonic of the frequency from rectifier 9a is selected which is of the order of 10 kilocycles. Thermionic tube 23a amplifies the energy of this frequency and transfers the same to movable coils 16a-17a through phase-splitting circuit 18a-19a. The transmitter, the frequency of the emanating energy from which is to be controlled, comprises 30 40 principally thermionic tube oscillator 26a, thermionic tube amplifier 27a and radiating or load circuit 29a. The frequency of the energy from the transmitter may be selected as of the order of 500 kilocycles. This energy beats with the received energy of 510 kilocycles and in the output circuit of rectifier 13a the beat frequency is of 10 kilocycles, being the difference between the two.

Since this is also the 51st subharmonic or 35 submultiple frequency of the received energy, movable coils 16a-17a remain steady. Should the frequency of oscillator 26a increase or decrease from the value of 500 kilocycles, a rotating field between coils 14a-15a and 16a-17a would be created and a torque exerted upon movable coils 16a-17a. The movement of coils 17a and 16a would be transmitted to frequency controlling element 25a which would be moved to change the frequency characteristics of the circuit restoring the same to the original frequency of 500 kilocycles.

Many different values may be chosen for 40 the frequencies employed. For instance at the master transmitting station illustrated in

Fig. 1, the energy in the input circuit of thermionic tube 13 may be harmonic frequencies of the energy from oscillators 6 and 26. Accordingly any submultiple frequency may be selected from source 6. In like manner the frequencies chosen at the remote transmitting station will be governed accordingly. The beat frequency energy may be supplied to the movable coils and the energy of submultiple frequency supplied to the stationary coils. Any suitable type of thermionic tubes may be employed. Additional stations may be controlled by either transmitting station. Thus, in the example given, the energy radiated from antenna 29a of transmitter 26a, 75 27a has a frequency of 500 kilocycles. This 500 kilocycle frequency may be employed to serve as a standard frequency for additional transmitters.

If desired the 500 kilocycle energy received 80 may be employed instead of source 7, shown in Fig. 1, thereby establishing a definite and uniform frequency separation between the frequency of the energy radiated from the two transmitters. Suppose that element 7, 90 shown in Fig. 1, is replaced by a suitable energy collecting system receiving the energy from transmitter 26a-27a, shown in Fig. 2. The 500 kilocycle energy would beat with the energy of transmitter 26-27 which is 510 95 kilocycles producing a beat frequency of 10 kilocycles as formerly when element 7 was employed. Since constant frequency element 7 is not employed the frequency of the energy radiated from antenna 29 would be governed or controlled by the frequency of the energy received from transmitter 26a-27a. The condition can now be realized whereby one station acts as a standard frequency station for another station and also where each station controls the other station. The primary requirement is that broadcasting stations, and code stations as well, be separated by a definite frequency band. The regulatory authorities of the United States insist that the frequency of each station be controlled within reasonable limits as predetermined according to geographical and frequency separation.

Since the geographical separation is already established all that remains is that each station operate on the proper frequency. In the present system of my invention it is obvious that any number of stations may be interrelated to effect the necessary frequency separation at all times. For instance, in the example given where element 7 is removed and the energy from transmitter 26a-27a is employed to control the frequency of the energy from transmitter 26-27, the frequency separation between the radiated energy from the two transmitters is automatically and accurately maintained constant. Since the frequency separation is fundamentally the only consideration of importance in frequency allocation, it is obvious that from a constant 100 105 110 115 120 125 130

frequency station all other stations may be controlled in that they will automatically remain separated a given frequency range. This is especially valuable in the broadcast band of frequencies.

As an example of the effectiveness of the remote control of frequency according to my invention the following frequency relations are given:

	Kilocycles
Master station constant frequency element	400
Master station transmitter frequency	410
Master station beat frequency	10
Master station 40th subharmonic frequency	10
Station A:	
Station receiver frequency adjustment	410
Station transmitter frequency adjustment	420
Station beat frequency adjustment	10
Station 41st subharmonic frequency adjustment	10
Station B:	
Station receiver frequency adjustment	420
Station transmitter frequency adjustment	430
Station beat frequency adjustment	10
Station 42nd subharmonic frequency adjustment	10

From the foregoing examples, it is clear that the master station will control the frequency characteristics of Station A. Station A will in turn control the frequency characteristics of Station B. Should the frequency of the master station change in value it is obvious that the frequency of both Station A and Station B will change in like proportion. This automatically prevents heterodyne between the stations since the frequency difference is determined by the frequency change of the master station. Any number of stations may be interlinked in this manner and the frequency separation between the stations automatically controlled within the desired limits of frequency.

It is obvious that the frequency control arrangement of my invention may be employed to control receiving apparatus in a manner similar to that shown and described. I realize that many modifications of my invention are possible. Any satisfactory relation of received to transmitted frequency may be employed as well as any system for producing submultiple frequencies. It is to be understood that the embodiments of my invention are not to be restricted by the foregoing specification or by the accompanying drawings but only by the scope of the appended claims.

What I claim as new and desire to secure by Letters Patent of the United States is as follows:

1. In a radio system, a standard transmitting station comprising a transmitting antenna, a source of power oscillations connected to said antenna, a source of oscillations of standard frequency, frequency stabilizing means for maintaining the frequency of said power oscillations equal to said standard frequency, a controlled station geographically separated from said standard station comprising a receiving antenna and an independent transmitting antenna, said receiving antenna being adapted to receive energy from said transmitting antenna of said standard station, a second source of power oscillations

connected to said independent transmitting antenna, frequency stabilizing means for maintaining the frequency of said second source of power oscillations in a determined relation with reference to the oscillations received on said receiving antenna from said standard station, each of said frequency stabilizing means comprising tuning means for controlling the frequency of said power oscillations, means for producing sub-harmonics of said standard frequency and said received oscillations respectively, and means responsive to the difference between one of said sub-harmonics and the beat frequency between said power oscillations and said standard or received oscillations respectively for actuating said tuning element.

2. In a radio system, a plurality of stations geographically separated from each other, each of said stations comprising a transmitting antenna and a receiving antenna, receiving apparatus at each of said stations adapted to receive oscillations from a remote transmitting antenna, and frequency stabilizing means at each of said stations for maintaining a fixed frequency relation between the frequency of oscillations received at said station and the frequency of oscillations transmitted from said station, said frequency stabilizing means comprising tuning means for controlling the frequency of said power oscillations, means for producing sub-harmonics of the received oscillations, and means responsive to the difference between one of said sub-harmonics and the beat frequency between said power oscillations and said received oscillations for actuating said tuning element.

3. In a radio system, a plurality of stations geographically separated from each other, each of said stations comprising a transmitting antenna and a receiving antenna, receiving apparatus at each of said stations adapted to receive oscillations from a remote transmitting antenna, and frequency stabilizing means at each of said stations for maintaining a fixed frequency relation between the frequency of oscillations received at said station and the frequency of oscillations transmitted from said station, said frequency stabilizing means comprising tuning means for controlling the frequency of said power oscillations, means for producing sub-harmonics of the received oscillations, and means responsive to the difference between one of said sub-harmonics and the beat frequency between said power oscillations radiated from said transmitting antenna and said received oscillations for actuating said tuning element.

LAWRENCE A. HYLAND.
